UNITED STATES PATENT OFFICE.

EDGAR EBENEZER MANN, OF WATERBURY, CONNECTICUT, ASSIGNOR TO
ADELAIDE E. MANN, OF WATERBURY, CONNECTICUT.

TENT.

No. 809,516.

Specification of Letters Patent.

Patented Jan. 9, 1906.

Application filed March 23, 1905. Serial No. 251,694.

To all whom it may concern:

Be it known that I, EDGAR EBENEZER MANN, a citizen of the United States, residing at Waterbury, in the county of New Haven and State of Connecticut, have invented a new and useful Tent, of which the following is a specification.

This invention relates to improvements in tents, and has for its principal object to provide a tent of very simple construction which may be readily set up or struck and packed in small compass for transportation.

A further object of the invention is to provide a tent structure of such nature that it may be placed in position and firmly secured without the aid of guys, ropes, or pins and which when once erected is self-supporting to the extent that its center pole may be removed, so that the whole of the interior of the tent will be free and unencumbered.

A still further object of the invention is to provide a tent in which all of the frame members may be made of very light metal tubing, so that when folded for transportation it may be conveniently carried and may be set up or struck with but slight exertion.

With these and other objects in view, as will more fully hereinafter appear, the invention consists in certain novel features of construction and arrangement of parts herein-after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a perspective view of a tent constructed in accordance with the invention. Fig. 2 is a sectional elevation of sufficient of the same to illustrate the invention, the parts being shown in open position. Fig. 3 is a similar view with the members of the frame collapsed. Fig. 4 is a side elevation showing the manner in which the cover of the tent is wrapped around the frame members. Fig. 5 is a plan view of the head-plate detached. Fig. 6 is a sectional elevation of the same, illustrating the employment of separate pivot-lugs secured to the plate. Fig. 7 is a plan view of the stretcher-carrying slide detached. Fig. 8 is a sectional elevation of one of the

side bars, illustrating also the upper portion 55 of one of the corner-posts. Fig. 9 is a plan view of one of the corner-posts and the end portions of adjacent side bars. Fig. 10 is a detail perspective view of one of the side bars. Fig. 11 is a detail sectional view of 60 one of the flap-closing devices.

Similar numerals of reference are employed to indicate corresponding parts throughout the several figures of the drawings.

In carrying out the present invention the 65 canvas or other fabric is supported on a suitable frame, which may be formed of very light metal tubing, the various members of the frame being pivotally connected or provided with detachable connections and the 70 parts being so arranged as to permit ready folding into small compass.

The various parts of the tent receive preliminary support from a center post 10, that is provided with a centrally-disposed guiding-opening for a ground-pin 11. The lower end of the post is protected by a thimble or ferrule 12, having a tapered opening, and at its upper end is secured a plug 13, having a threaded portion, which projects beyond the 80 end of the post. The pin 11 has a pointed end, which may be inserted in the ground, and its upper end is provided with a projecting arm 14, that extends through a vertical slot 15, formed in the post, the arm affording 85 a striking-face for the driving-aul, so that the pin may be driven into the ground to any required depth, and when inserted the proper distance either the pin or the post may be turned until the projecting arm is inserted in 90 one or other of a plurality of stepped recesses 16, that open into the vertical slot, thus firmly locking the center post to the ground.

The folding frame structure includes a vertically-disposed tube 17, preferably formed 95 of metal tubing and of square or polygonal form in cross-section, the lower end of said tube being provided with a plug 18, the projecting portion of which is threaded, and the threaded portions of the plugs 13 and 18 are 100 detachably connected by a threaded coupling-sleeve 19. The upper end of the tube 17 is provided with a second plug 20, having its upper threaded end extending beyond the top of the bar, the lower portion of the plug 105 being set within the top of the tube and held by one or more countersunk screws 21, the plug serving to stiffen and strengthen the end

of the bar, but affording no projections which might interfere with the folding or unfolding operations or prevent packing the tent within small compass.

- 5 On the threaded plug 20 is screwed a head-plate 23 of a contour corresponding to that of the tent—that is to say, rectangular for a four-wall tent, hexagonal for a six-wall tent, or octagonal for an eight-wall tent.
- 10 This plate is provided with a number of openings 24, separated by arms 25, and on the arms are vertical partitions 26, forming spaces for the passage of air in order to ventilate the tent. To the outer edge of the head-plate
- 15 are secured hinge members 27, which may be cast integral with the plate or formed separately and secured thereto, and to these hinged members are pivoted the inclined rib or rafter members 28. After the head-plate
- 20 has been screwed into place a small post 30 is screwed on the projecting portion of the thread-plug 20, this post being also formed of hollow tubing and being provided at its upper end with a plug 31, having a threaded portion
- 25 arranged to receive a top plate 33, that is provided with openings of a number corresponding to the number of openings 24 on the head-plate, and the partitions 26 are extended up to the arms which separate the
- 30 openings of the top plate, thus forming a series of vertical passages through which heated or impure air from the tent may escape. The periphery of the top plate 33 is provided with a continuous annular groove 35 for the
- 35 reception of the peripherally-corded top of the tent, the latter being secured in place in any suitable manner.

The threaded portion of the plug 31 extends for some distance above the top plate

40 and is arranged to receive a hood 36, preferably an approximately dome-shaped piece of metal that will prevent the entrance of rain to the tent and will serve as a ventilator. Above this the threaded portion of the plug

45 receives a reducing-coupling 37, to which is screwed the foot of a flagstaff 38.

Mounted on the non-circular bar or tube 17 is a vertically-movable slide 40, the contour of which corresponds to the contour of the

50 head-plate, being octagonal in form in the present instance, and each of the sides of said slide is provided with hinged members 41, to which are pivoted hinge members 42, carried at the inner ends of stretchers 43, and in assembling these parts the hinge members are preferably inserted within the ends of the tubes of which the stretchers are formed and then confined in place by cross-pins or screws. The slide may be moved downward on the

60 bar 17 until the stretchers 43 are in the horizontal position and then locked in place by a detachable pin 40', passing through both the slide and tube or may be moved upward after the removal of the pin 40' until said stretchers assume a position approximately parallel

with the bar, this movement causing the ribs or rafters 28 to move inward and the several members being thus folded within small compass.

At the outer end of each stretcher 43 is secured a small sleeve 45, connected by hinge members 46 to a sleeve 47 on the rib 28, while the extreme outer end of the stretcher abuts against the under side of the rib and forms a support therefor, as shown in Fig. 2. The sleeve 45 is further provided with a pivotal connection 48 at the top of a corner-post 50, and each corner-post is formed of a metal tube having a bottom ferrule 51, which rests on the ground. Within the tube 50 is a pin 53, having at its upper end an arm 54, that projects through a slot 55 in the tube and is arranged so that it may be driven by a maul, and when embedded in the ground the arm 54 may be inserted in any one of a number of recesses 56 formed in the tube, said recesses opening into the slot 55. The upper end of the corner-post 50 is provided with a cap-piece which rests against the inner side of the rib 28 and against the under side of the stretcher 43, and it will be seen that when the parts are once adjusted to the proper position the main center post 10 will be unnecessary and may be removed, so that the whole of the interior of the tent will be free from obstruction.

Each of the cap-pieces at the outer ends of the posts 50 is provided with a socket 60, arranged to receive the laterally-projected ribs 61, carried by arms 62, projecting from the ends of the side bars 63 of the tent-frame. When these bars are formed of wood, they are provided with end slots 64, into which the arms 62 are inserted and secured by cross-pins or rivets, while the ears 61 project in such manner that they may be conveniently inserted in or removed from the sockets 60 or the side bars may be formed of metal tubes, to which the inner members are riveted or otherwise secured.

To each of the side bars 63 is secured a number of eyes or hooks 67 for the support of rods 68, and on these rods are hung the side walls of the tent, preferably by small hangers 69, having hook portions at each end, one for engagement with an eye at the top of the canvas and the other arranged to fit over the rod 68, so that the wall of the tent may be opened or closed by sliding the hangers on the rods.

It is desirable in many cases to lock the side walls of the tent to prevent intrusion, and for this purpose one side wall or, if necessary, all of the side walls are formed of two separate pieces of canvas, at the meeting edges of which are secured clips, each clip comprising a pair of plates 70 and 71 and a locking member 72. The plate 70 is riveted or otherwise secured adjacent to one edge of the canvas and has an opening 73, while the

opposite plate is secured to the opposite edge and has pivot-eyes for the reception of end pintles projecting from the member 72, so that when the latter is inserted through the 5 opening 73 and turned the two edges of the canvas will be locked together, and as these fastening devices are on the inner side of the wall they cannot be opened from the exterior.

10 After the tent has been set up the center post may be removed and will not be required until the tent is to be struck, after which it is placed in position. The side walls of the tent are then removed by lifting the hangers 15 69 from the rod 68, and after this the side bars 63 are removed. It is then necessary to push the slide 40 upward to the position shown in Fig. 3, after first turning in the corner-posts 50, all of the parts folding up umbrella fashion in the manner shown in Fig. 4.

20 It will be observed that the tent may be erected without the employment of any guys or stays and without the employment of the usual tent-pins and may be readily folded in 25 small compass for transportation.

Having thus described the invention, what is claimed is—

1. A foldable tent having a sectional center post, the lower section of which is attached 30 to and forms a support for the upper section during the erecting and striking of the tent, and is detachable to leave a clear space below the upper section when the tent is in use, corner-posts, rafters connecting the corner-posts to the upper end of said upper section, a slide movable on said upper section, and 35 stretcher members extending between the rafters and the slide.

2. A foldable tent having a center piece 40 formed of upper and lower detachable sections, the lower section constituting a support for the upper section during the erecting and striking of the tent, and being detachable to leave a clear space below the upper 45 section when the tent is in use, corner-posts, rafter members extending between the upper end of the upper section and the corner-posts, a slide movable on said upper section, stretcher members extending between the 50 outer ends of the rafters and the slide, and means for locking said slide to the lower portion of said upper section.

3. A folding-tent frame, including a center post formed of upper and lower detachable 55 sections, the lower section serving to support the upper section during erecting and striking, and being detachable to leave a clear space under the upper section when the tent is in use, corner-posts, rafters or stretchers

pivotaly connected to the corner-posts, the 60 rafters having a pivotal connection with the upper end of the upper section of said center post, and the stretchers forming a truss and supporting the upper section of the center post. 65

4. In a folding-tent frame, a sectional center post, of which the lower section forms a support for the upper during erecting and striking of the tent, and is detachable to afford a clear space below the upper section 70 when the tent is in use, said upper section being non-circular in form, a slide having a non-circular opening mounted on said upper section, a head-plate secured to the upper section, corner-posts, stretchers extending 75 between the slide and the corner-posts, and rafters pivotally connected to the head-plate and to the upper ends of the stretchers.

5. In a folding tent, a sectional center pole, formed of metal tubing, a head-plate 80 carried by the pole and provided with a plurality of air-escape openings, a top plate also carried by the pole and provided with similar openings, said top plate being provided with a peripheral groove to receive the top of 85 the tent fabric, vertical partitions extending between the head-plate and top plate, and forming channels for the passage of air, and a protecting-hood carried by the pole and extending over the top plate. 90

6. In tents, a hollow post, open at its lower end and provided with a slotted wall, and a ground-pin arranged within the post and having a driving-head extending through the slot. 95

7. A tent-post formed of a tube open at its lower end and provided with a slotted wall, there being recesses formed in the walls of the slot, a driving-pin arranged in the post and having an arm projecting through the 100 slot to form a driving-head, said arm being insertible in any one of the recesses to lock the post to the ground.

8. In a tent-post, a hollow tube having at its lower end a ferrule provided with a tapered opening and having a vertical slot, the edges of which are recessed, and a ground-pin arranged within the tube and having an arm projecting through the slot and forming a driving-head. 105 110

In testimony that I claim the foregoing as my own I have hereto affixed my signature in the presence of two witnesses.

EDGAR EBENEZER MANN.
